2 Claims

ABSTRACT OF THE DISCLOSURE

A conventional small arms magazine is provided with an elongated longitudinally grooved follower guide adjacent the magazine interior rear wall. A follower, having a rearwardly projecting tongue slidably positioned within the follower groove with a further rearwardly projecting finger at a lowermost portion of the tongue, moves cartridges upwardly and into the weapon chamber. The follower guide has a slot extending transversely to the groove that slidably receives a latch which is moved upwardly into the operative path of a cartridge chambering bolt after the last cartridge in the magazine has been expended.

The invention described herein may be manufactured, used, and licensed by or for the Government for governmental purposes without the payment to us of any royalty thereon.

Military field exercises involving simulated combat conditions are essential in the training of modern infantry units. During these exercises, as well as on other occasions, the small arms carried by the infantrymen are provided with blank cartridges to add a touch of realism to the maneuvers. In the past, casualties have occurred during these exercises which were attributed to the inadvertent presence of ball type ammunition among the blank cartridges and some attempts have been made to obviate this hazardous condition.

A prior art blank firing safety attachment for small arms, is illustrated in U.S. Patent 2,355,045, issued to H. R. Audet. As seen in the Audet patent, magazines may be adapted to accommodate blank cartridges by providing the magazines with inserts in their forward ends. These inserts reduce the magazine length for the reception of blank cartridges which are generally shorter than ball type cartridges. The presence of the insert in this type of magazine positions the forwardmost portion of the cartridge rearwardly of the cartridge chamber at a distance which is not conducive to good cartridge chambering. For example, a ball type cartridge in a magazine having no insert, will have its tip or point positioned close to the rear of the cartridge chamber before the bolt closes and chambers the cartridge. The position of the cartridge in conjunction with the chamfered surfaces on the rear peripheral surface of the cartridge chamber, facilitate positive and rapid chambering. In a magazine having a forward insert and a blank cartridge, the forwardmost portion of the cartridge must travel a greater distance than its ball type counterpart, and, lacking the smooth contour of a projectile or ball, cartridge chambering becomes erratic and frequent gun jams result.

It is, therefore, an object of this invention to provide a small arms magazine with an adapter assembly which facilitates the chambering of blank cartridges.

It is another object of this invention to provide a magazine adapter assembly which will prevent any ball type cartridges from being loaded with blank cartridges.

2

A further object of this invention is the provision of a magazine adapter assembly which may be utilized in conjunction with existing magazines that can be retrofitted in the field.

These and other objects are effected in the present invention by providing a conventional small arms magazine with an elongated longitudinally grooved follower guide positioned within the magazine adjacent the magazine rear wall. The magazine follower has a rearwardly projecting tongue slidably positioned within the groove with the weapon, the rearwardly projecting follower finger A latch, slidably positioned within a slot in the follower guide, reciprocates between an upper position and a lower position in response to the translation of the follower within the magazine. After the last blank cartridge contained in the magazine has been fired and ejected from the weapon, the rearwardly projecting follower finger will engage the latch and move it upwardly into the operative path of the cartridge chambering bolt to thereby maintain the weapon chamber in an opened condition. The presence of the follower guide at the rear of the magazine prevents long ball type cartridges from being inadvertently loaded within the magazine and also facilitates chambering of the shorter blank cartridges by positioning the cartridge forwardmost portion in close proximity with the rearwardmost end of the weapon chamber.

Additional features and advantages of the invention will become apparent in the following description taken in conjunction with the accompanying drawings in which:

FIG. 1 is a perspective view, partially broken away and sectioned, showing a small arms magazine embodying features of the invention.

FIG. 2 is a perspective, fragmentary view of the magazine adapter of FIG. 1 illustrating the cooperation between the follower, the follower guide and the latch.

FIG. 3 is a perspective, fragmentary view of the adapter assembly of FIG. 2 with the follower and latch shown in the empty magazine uppermost position.

A conventional small arms weapon magazine 10 (FIG. 1), having front, rear and side walls, 11, 12 and 13 respectively, and a bottom wall 12A, is provided with an elongated follower guide 14. Follower guide 14, positioned within magazine 10 adjacent the interior of rear wall 12, has a front wall 14A provided with a longitudinal groove 15 (FIG. 3) extending along its entire length. Follower guide 14 may be constructed from any suitable material such as metal or plastic as may be dictated by good economical design considerations.

A cartridge support or follower 16 having a integral cartridge-shaped form 17, is positioned within magazine 10 and is urged upwardly by the action of helical compression spring 18 which is positioned between follower 16 and the lower magazine wall. Follower 16 has forward appendages 19 which engage limits or stops 20 that contain follower 16 within magazine 10. Follower rear end 20A has a downwardly projecting portion 21 integral therewith, and a rearwardly projecting tongue 22 extending along portion 21 and which has a further rearwardly projecting finger 23 at its lowermost end. As one skilled in the art would readily observe, the depth of groove 15 in the forward face of follower guide 14 must be such as to permit free translation relative to magazine 10 of follower 16 and its rearwardly projection portions.

A slot 24 is formed within the rear wall 15A of follower guide 14 and extends transversely to longitudinal groove 15. The depth of slot 24 is such that an opening or aperture 25 (FIG. 3) is formed at the intersection between slot 24 and groove 15. Follower finger 23 is positioned in registry with aperture 25 in response to the upward translation of follower 16. The position of slot 24 relative to the magazine lower wall, as well as the slot

width in the upward direction, are dependent upon the design factors of latch 26 which will next be discussed.

Latch 26 has an upwardly protruding portion 27 and a lower portion 28 integral therewith which extends transversely to groove 15 and which is slidably positioned within slot 24. The length of latch upwardly protruding portion 27 is adjusted so that the uppermost surface thereof, 29, is flush with follower surface 30. The amount of upward travel of latch 26 is adjusted by the width of slot 24, which in turn depends upon the amount of surface area 31 needed to engage the forward surface of a cartridge chambering bolt when latch 26 is positioned within the operative path of the bolt. Latch 26 is moved into the bolt path when surface 32 on follower finger 23 engages surface 33 on the bottom of latch 26. Engagement between latch surface 31 and the forward surface of the cartridge bolt will block the bolt in its rearwardmost position.

Parallel slits 35, which extend longitudinally of magazine 10 in wall 13, aid a rifleman in the visual determination of the magazine contents.

The skilled artisan will readily perceive that the present invention is adapted for field retro-fitting in a standard ball type magazine with the least amount of tools and skill. For example, the follower in a standard magazine such as 10, may be readily removed by deforming stops 20 and removing the follower. Follower 16 may then be inserted within magazine 10. Follower guide 14, with latch 26 positioned within slot 24, is then forced downwardly into magazine 10 adjacent to wall 12. By properly dimensioning follower guide 14 a snug fit may be achieved which will retain guide 14 in its proper position within the magazine. Stops 20 may then be deformed into their former position and the retrofitting of the standard magazine is complete.

In operation, magazine 10 is loaded with a plurality of blank cartridges, and, after all but the last cartridge 40 has been fired from the weapon, the follower will be positioned within magazine 10 as shown in FIG. 1. In this position surface 32 on follower finger 23 will engage surface 33 on latch lower portion 28. After cartridge 40 has been fired and ejected from the weapon, spring 18 will urge follower 16 upwardly with finger 23 simultaneously moving latch 26 into its uppermost position at which time surface 31 on latch 26 will engage the forward surface of a cartridge chambering bolt and will hold it in its rearwardmost position until the rifleman reloads the weapon.

In light of the foregoing description it is apparent that

a blank cartridge adapter is available for a small arms magazine which eliminates the safety hazards which have been associated with the prior art devices.

We claim:

- 5 1. In a small arms magazine having front and rear walls and a lower wall, the combination with said magazine of an adapter assembly for feeding blank cartridges, said assembly comprising:
- 10 a cartridge follower having an integral downwardly protruding portion at a rear end thereof, said portion having a tongue extending rearwardly therewith, said tongue having a finger projecting rearwardly therefrom at a lower end thereof,
- 15 an elongated follower guide positioned within said magazine along said rear wall, said guide having a front wall with a longitudinal groove therein slidably receiving said tongue, said guide further having a rear wall with a slot therein extending transversely to said groove, said slot located a predetermined distance upwardly from said lower wall and intersecting said groove to define a rectangular aperture for registry with said finger,
- 20 a latch having an upwardly protruding portion and a lower portion extending transversely thereto at a lowermost end thereof, said lower portion being slidably positioned within said slot for reciprocating between upper and lower positions upon operative engagement with said finger, and
- 25 means within said magazine for urging said follower upwardly so that when a last cartridge has been expended, said finger will engage said latch and move it into the operative path of a cartridge chambering bolt.
- 30 2. The magazine as recited in claim 1 wherein said urging means includes a compression spring positioned between said follower and said lower wall.
